513.

Daniel D. Shackford & Theodore Shackford of Westbrook
State of Maine.

Letters Patent

The schedule referred to in these Letters Patent, and making part of the same containing a description in the words of the said Daniel D. Shackford & Theodore Shackford, themselves of their improvement in the machine for breaking Dough;

It is known that we Daniel D. and Theodore Shackford of the town of Westbrook in the county of Cumberland, and State of Maine, have made an improvement in the useful art being a machine for breaking Dough for bread called "Shackford's Dough Breaker," which is described as follows, reference being had to the accompanying drawings of the same making part of this Specification.

1. A suitable frame is constructed such as is represented at A, - in the centre of which is erected a post, B, on which is fastened and turns, horizontally with it, a circular platform C, on which the dough is to be broken, having a circular rim or curb D, wound its circumference forming a trough, this platform turns upon antifriction roller E supported in another frame F beneath the revolving platform, motion is given to the platform by cast iron gearing, consisting of a circular rack G, fastened to the under side of the platform, into which works a small vertical pinion H, fixed on the end of a horizontal line shaft, I, having on its ^{other} end a cog wheel K, into which works another cog wheel L whose shaft has a crank M, on its end by which the machine is operated, this shaft and the line shaft, being supported by the standards N, in which they turn in suitable metallic boxes, one end of the line shaft turns in a box in a standard on the second frame, -

In the circular trough and revolving on it, is placed a fifth part of a cone O, for breaking the dough, having an axis P passing through its centre, by which the cone is suspended from

the ends of a chain or rope Q passing round a shaft R and over a pulley S, the shaft R having a crank handle T, on one end by which it is turned in order to raise or lower the same, a cog-wheel & pulley being fixed on the other end of this shaft, to cause it in any required position, one end of the axle P, has an eye passing over the centre post to allow it to work up and down on the same. The dough being first prepared for the breaking in the trough is placed upon the revolving platform—the crank handle is turned, this turns the cog-wheel on its shaft which turns the cog-wheel on the end of the live shaft and with it the live shaft, and pinion on its other end which works in the circular rack, fastened to the under side of the circular platform, and thus turns it with the dough thereon in a horizontal position, the dough passing under the fluted cone or breaker, which at the same time has a rotary motion, its axle being suspended in the ends of the chain or rope and bearing horizontally against the centre post, and against one of the side posts of the frame. This operation is continued till the dough be sufficiently broken.

The machine may be operated by Manual, Horse, Water, or other power.

What we claim as a new and as of our invention and which we desire to secure by Letters Patent, consist in the combination and arrangement of the several parts of the before described machine for breaking dough.
